UNITED STATES PATENT OFFICE.

AI B. SHAW, OF MEDFORD, MASSACHUSETTS, ASSIGNEE TO SHAW TIRE COMPANY, A CORPORATION OF MASSACHUSETTS.

INNER TUBE.

1,242,252.

Specification of Letters Patent.

Patented Oct. 9, 1917.

Application filed June 2, 1916. Serial No. 101,853.

To all whom it may concern:

Be it known that I, AI B. SHAW, a citizen of the United States of America, and a resident of Medford, in the county of Middlesex and State of Massachusetts, have invented certain new and useful Improvements in Inner Tubes, of which the following is a specification.

This invention relates to inner tubes for 10 tires and has for its object the production of a tube which will retain air under pressure even after said tube has been punctured.

The invention consists of a tube molded with a plurality of inwardly extending cup-shaped members which are substantially fixed when said tube is deflated but which are adapted to be forced outwardly against the inner face of the shoe when the tube is inflated, thereby causing the material of said 20 tube to be compressed sidewise in every direction.

The invention further consists of certain novel features of construction and arrangement of parts which will be fully understood 25 by reference to the description of the drawings and to the claims hereinafter given.

For the purpose of illustrating the invention, one preferred form thereof is illustrated in the drawings, this form having 30 been found to give satisfactory and reliable results, although it is to be understood that the various instrumentalities of which the invention consists can be variously arranged and organized and that the invention is not 35 limited to the precise arrangement and organization of these instrumentalities as herein shown and described.

Of the drawings:

Figure 1 represents an elevation of an inner tube of usual construction.

Fig. 2 represents a transverse section through a tire and showing a cross section of a tube embodying the principles of the present invention, said tube being shown 45 deflated.

Fig. 3 represents a similar view with the inner tube inflated.

Fig. 4 represents an elevation of a portion of the tube, showing the manner of intersection of the inwardly projecting cup-shaped members.

Fig. 5 represents a section of the same on line 5-5 on Fig. 4, and

Fig. 6 represents a section of the same on 55 line 6-6 on Fig. 4.

Similar characters designate like parts throughout the several figures of the drawings.

In the drawings, 10 represents an inner tube of usual construction. In carrying out 60 the present invention this tube is molded with a plurality of inwardly extending cup-shaped members 11 formed therein, these cup-shaped members being substantially fixed when the inner tube is deflated. Preferably the cup-shaped members 11 are so constructed that they intersect each other on the lines 12 and the material on these lines is slightly concaved, as indicated at 13 in Figs. 2 and 5 of the drawings.

Between the concavities formed in the outer surface of the tube 10 are a plurality of bearing surfaces 14 which are adapted to bear against the inner face of the shoe 15 when the tube 10 is inserted therein. The 70 tubes 10 with the inwardly extending cup-shaped members formed therein are constructed to fit the shoes 15 with the bearing surfaces 14 in contact with the inner wall thereof, as shown in Fig. 2 of the drawings.

The curvature of each cup-shaped member is greater than the curvature that said cup-shaped member would assume when the inner tube was inflated and the outer wall of each cup-shaped member pressed into contact with the inner wall of the shoe 15, as shown in Fig. 3 of the drawings.

It is obvious that when the tube 10 with the inwardly extending cup-shaped members formed therein has been inserted into the 80 shoe 15 and the tube inflated, the pressure of the air within said tube will force the material forming the cup-shaped members 11 outwardly into contact with the inner wall of the shoe 15, and in so doing the material 85 will be compressed sidewise in every direction.

When inflated, the tube assumes the condition shown in Fig. 3 of the drawings, and it is obvious that the tube will assume this 100 condition when the air contained therein has received its first compression. When the tube 10 has assumed the condition shown in Fig. 3 of the drawings, the air therein is further compressed and the entire inner wall 105 of said tube is subjected to the necessary pressure required to retain the tire inflated and support the weight that must be sustained thereby.

In case a nail or other member causes a 110

puncture through the shoe 15 and through the inner tube 10, the pressure of the compressed air within the tube 10 will cause the material forming the tube to grip upon the 5 surface of the puncturing member and ordinarily retain it in position.

Should, however, the puncturing member become dislodged, the pressure of the compressed air within the tube 10 will cause the 10 walls of the puncture to immediately come into contact with each other and thereby prevent any leakage of the air within the tube 10.

It is self-evident that, when the tube has 5 been inflated, the material of said tube will have become compressed sidewise in every direction and the tendency of said material would be to expand, so that if any ordinary sized opening is made through the walls of 20 the tube, the expansion of the material will immediately close the same.

This makes a very effective inner tube for

tires of motor cars, inasmuch as any punctures which may be created therein will be self-closing, and the tire trouble now so 25 common will be reduced to a minimum.

It is believed that the many advantages of this invention will be fully understood from the foregoing description.

Having thus described my invention, I 30 claim:

1. An inner tube provided with a plurality of inwardly extending cup-shaped members intersecting each other so that the material on each line of intersection will 35 have an inward curvature.

2. An inner tube provided with a plurality of inwardly extending cup-shaped members intersecting each other and forming narrow dividing ridges the outer edges 40 of which are hexagonal in outline.

Signed by me at 4 Post Office Sq., Boston, Mass., this 19th day of May, 1916.

AI B. SHAW.
